A. B. Reavis

ATTORNEY

UNITED STATES PATENT OFFICE.

SAMUEL S. BALL, OF JERSEY CITY, NEW JERSEY, ASSIGNOR TO BETHLEHEM STEEL COMPANY, A CORPORATION OF PENNSYLVANIA.

STOPPER ROD.

Application filed June 20, 1923. Serial No. 646,534.

To all whom it may concern:

Be it known that I, SAMUEL S. BALL, a citizen of the United States, and residing at Jersey City, Hudson County, State of New Jersey, have invented certain new and useful Improvements in Stopper Rods, of which the following is a specification.

My invention relates to stopper rods of the character intended for use with ladles employed in metallurgical operations and it has for an object to provide apparatus of this character which shall be durable and which shall be capable of ready repair.

More particularly, my invention has for an object to provide an inner rod having a flange for supporting refractory sheathing or cylinders, the stopper head being detachably connected to the rod at the side of the flange opposite to the refractory sheathing or cylinders.

A further object of my invention is to provide a novel construction of drop-forged rod for supporting the refractory material and the stopper head in a stopper rod construction.

The novel features of construction will be understood from the following description and claims taken with the accompanying drawings.

30 In the drawing, the figure is a fragmentary sectional view of my improved stopper rod.

Referring now to the drawing for a better understanding of my invention, I show a stopper rod consisting of an inner supporting rod member 10, sheathing or refractory cylinders 11, and a stopper head 12.

The rod member 10 comprises a shank portion 13 and a threaded tip portion 14 separated by a circumferential flange 15 having end faces 16 and 17 which are preferably substantially frusto-conical and which join the shank 13 and the threaded portion 14 by fillets.

The refractory material or sleeves surround the shank portion 13 and they are sustained by the face 16 constituting a shoulder on the flange 15.

The stopper head 12 is provided with a central opening 18 having a threaded portion 19 fitting the threaded portion 14 of the rod and a countersunk portion 20 which surrounds the flange 15 and provides a shoulder 21 which is formed to fit against the flange face 17.

55 The spaces between the refractory ma-

terial or cylinders 11 and the shank 13 and between the adjacent end faces of the refractory material 11 and the stopper member 12 are preferably filled with clay or any other suitable material as indicated, at 22, 60 so that the entire construction may be essentially solid and the contact of molten metal or the ready transmission of heat therefrom to the inner supporting rod 10 shall be limited.

Since stopper heads are ordinarily made of compositions consisting largely of graphite, I prefer to have the threads on the tip portion 14 and the threads 19 in the recess 18 rounded in order to provide both for the ready formation of threads in the head portion and for the formation of threads of adequate strength therein. It will also be noted that the threads are relatively large and of coarse pitch. This arrangement 75 simplifies the construction; and, since the weight of the refractory sleeves 11 is sustained by the collar 15, internal threads integral with the stopper head have sufficient strength to sustain the latter under 80 operating conditions.

Although it is not essential to my invention in its broadest aspects to provide the flange 13 with frusto-conical end faces joining the shank and thread portions by fillets, nevertheless I prefer to construct the central supporting rod member in this manner for the reason that manufacturing thereof by the drop forging process is rendered easier as sharp corners are avoided. Also end 90 faces constructed in this manner serve to center and to provide good seating for the adjacent refractory cylinder 11 and the stopper head 12.

From the foregoing, it will be apparent that I have devised a stopper rod construction in which the weight of the refractory material surrounding the shank portion of the supporting rod is sustained by a flange on the rod, thereby relieving the stopper head of any load except that due to its own weight. It will also be seen that the detachable connection between the stopper head 12 and the threaded rod tip 14 is arranged between the ends of the stopper head 12 in an axial direction, thereby permitting of the ready removal or replacement of the head 12 without in any way disturbing the refractory cylinders 11.

While I have shown my invention in but 110

one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

10 Having thus described the invention what is claimed as new and desired to be secured by Letters Patent is:

15 1. A stopper rod construction comprising a rod member having a supporting collar integral with and near to the lower end thereof and a threaded portion below the collar, refractory sleeve means surrounding the rod member and supported by the collar, and a stopper head made of refractory material and having integral internal threads provided in an axial recess and fitting the threaded portion of said rod.

20 2. A stopper rod construction comprising a rod member having a collar near to its lower end and a coarse-pitched, round-threaded lower terminal portion below the collar, refractory sleeve means surrounding the rod member and supported by the collar, and a stopper head made of refractory material and having integral internal coarse-pitched rounded threads fitting the threads of said terminal portions.

25 3. A stopper rod construction comprising a rod member having an integral collar near to its lower end and connecting means carried by the rod member below the collar, refractory sleeve means surrounding the rod member and supported by the collar, and a stopper member made of refractory material and having integral internal connecting means for cooperation with the first connecting means to secure the stopper member to the rod member.

40 4. A stopper rod comprising a rod member having a shank, a threaded tip, a circumferential flange between the shank and the threaded tip and having an upwardly extending substantially frusto-conical face, a plurality of refractory sleeves surrounding the shank, the lower face of the lowermost sleeve fitting the upper face of the flange, and a stopper member having a cen-

tral threaded portion fitting the threaded tip and a countersunk portion surrounding the flange.

55 5. A stopper rod comprising a rod member having an upper shank, a lower threaded tip, a flange between the shank and the tip provided with upwardly and downwardly extending substantially frusto-conical faces extending from the periphery of the flange to the shank and to the threaded tip respectively, a plurality of refractory sleeves surrounding the shank, the lower face of the lowermost sleeve fitting the upper frusto-conical face, and a stopper member having a central threaded portion fitting the threaded tip, a counter-sunk portion surrounding the shoulder and having a lower face fitting against the lower frusto-conical face.

60 6. A stopper rod comprising a central supporting rod member having a shank, a shoulder, and a threaded tip portion below the shoulder, a plurality of refractory sleeves surrounding the shank and supported by the shoulder, a stopper rod having a threaded connection with respect to the tip portion and a countersunk portion fitting around the shoulder, and packing material arranged between the shank and the refractory sleeves and between the adjacent ends of the lowermost sleeve and the stopper member.

65 7. A rod member for a stopper rod having a refractory covering and a stopper member comprising a shank, a threaded tip portion, a circumferential flange between the shank and the tip portion, the lateral faces of said flange being substantially frusto-conical and diverging inwardly towards the axis of the rod member.

70 8. An article of manufacture consisting of a drop-forged rod member having a shank, a threaded end portion, and a circumferential flange between the shank and the threaded end portion and having end faces which are substantially frusto-conical and which define fillets joining the shank and the threaded portion.

75 In testimony whereof I hereunto affix my signature this 14th day of June 1923.

SAMUEL S. BALL.
